UNITED STATES PATENT OFFICE.

GEORGE F. SISBOWER, OF FLUSHING, AND LOUIS E. PITTONI, OF NEW YORK, N. Y.,
ASSIGNORS TO MANHATTAN-ROME COMPANY, BRANCH OF ROME METALLIC BED-
STEAD CO., OF LONG ISLAND CITY, NEW YORK, A CORPORATION OF NEW YORK.

HOSPITAL BED.

Application filed September 20, 1922. Serial No. 589,329.

To all whom it may concern:

Be it known that we, GEORGE F. SISBOWER, a citizen of the United States, residing at Flushing, New York city, in the county of 5 Queens and State of New York, and LOUIS E. PITTONI, a subject of the King of Italy, residing at the city of New York, in the county of Queens and State of New York, have invented certain new and useful 10 improvements in Hospital Beds, the following being a full, clear, and exact disclosure of the one form of our invention which we at present deem preferable.

For a detailed description of the present 15 form of our invention, reference may be had to the following specification and to the accompanying drawings forming a part thereof, wherein

Fig. 1 is a side elevation with the bed 20 folded,

Fig. 2 is a similar view with the bed flat and

Fig. 3 a plan view;

Figs. 4 and 5 show details.

25 Our invention relates to a bed designed particularly for hospitals. It consists in certain arrangements for rendering a bed spring of the coil type foldable, so that it may be turned up under the back of the 30 patient and also under his knees as is often required in hospitals.

35 By the coil-type of bed spring we mean that type wherein there are a series of upright helical springs mounted on an underlying frame with the helicals loosely linked to one another at their tops usually by small horizontal helicals and enclosed by a light marginal retaining frame. The difficulty of folding or bending such a bed 40 spring has heretofore made it necessary in practice to use flat wire-fabric mattresses for hospital beds, such mattresses being much less comfortable than the coil-spring type. We have overcome this difficulty by 45 constructing the underlying frame in sections longitudinally free of one another, and making hinged joints in the upper marginal frame at the bending points. The axis of each bend is at the hinge joint in the marginal frame, while the lower frame sections 50 are so mounted as to draw away from or approach to one another as the bending occurs. In this way the upper surface of the

spring is maintained continuous, the sections merely standing at different angles and 55 the relation thereto of the stuffed mattress on top of the spring remains unchanged. The stuffed mattress conforms to the angular position of the said section, and the upright helicals remain at right angles 60 thereto. At the bottom, however, the continuity is broken by gaps between the separated sections, but such gaps do not affect the support of the stuffed mattress while the hinged marginal frame prevents the helicals 65 from sagging down sidewise when downward weight is applied to them at an angle when the bed is bent.

Referring to the drawings, A¹, A², A³ are the head, middle and foot sections of the 70 lower bed-spring frame. The middle section A² is shorter than the other two and the one at the foot shorter than the one at the head of the bed. When the spring is in its normal flat position (see Figs. 2 and 3) 75 A¹ and A² are then separated by a short gap, since the bending draws them apart (see Fig. 1) while A² and A³ are separated by a wide gap since the bending will draw them together (see Fig. 1). The upright 80 helicals B, B, etc., are mounted in groups on the respective sections, being seated on cross bars C, C, etc., as shown in Fig. 5. The bars C, C, etc., are flat and stand up edgewise beneath the helicals, but at their 85 ends they are twisted 90 degrees and also bent over so as to lie flat on the top of the side members of the aforesaid sections (see Figs. 3 and 5) and be riveted thereto. The bottom turn of each helical B is passed 90 through holes b¹, b² near the upper edge of the cross-bar C. By this means each helical is firmly seated on the frame and secured thereto. The linking of the helicals by small horizontal helicals is shown at the 95 lower right corner of Fig. 3. The entire series of helicals is enclosed by a rectangular marginal frame R having its side rails jointed at S¹ and S² and secured to each one of the outer row of helicals where it makes 100 tangential contact therewith.

The side-rail of the bedstead is shown at D in the form of an inverted channel bar. On each side-rail D the section A¹ has a link mounting by a long link F pivoted at f¹ to said section and a short link 105

f^2 pivoted thereto at f^5 . At its outer end link F is pivoted to a box-dog J which has an oscillating bearing on top of rail D by a pin j and on the under side a pawl 5 engaging rack teeth f^2 on the rail. The outer end of link f^2 is pivoted to a stud f^3 on the under side of rail D, and the same stud is connected by a parallel link f^1 to the link F. It will be perceived from 10 a study of Fig. 1 that when section A^1 is turned up by handle W from its normal horizontal position shown in Fig. 2 to the position it occupies in Fig. 1, it will rotate bodily around the axis of the hinge-joint 15 S^1 in the marginal frame bar. Its lower right hand end will be guided by link f^2 while the parallel link f^1 will draw link F, together with dog J, to the right and the engagement of the dog with the rack teeth 20 will hold the section at any desired elevation such as is shown, for example, in Fig. 1. The helicals B, B on section A^1 will remain at right angles thereto, although they are inclined with respect to rail D. 25 The weight of the occupant acting downwardly would tend to make the helicals sag down toward the right. Such sagging would tend to produce a downward thrust of the section at the marginal frame R 30 to which the helicals are attached but such thrust is resisted by the adjoining section of said marginal frame to which it is jointed. Consequently the helicals, when the section A^1 is elevated, act precisely as 35 they do when the section is in its normal horizontal position. It will be observed that section A^1 when lifted has been moved away at the bottom from section A^2 so that the gap between the two frame sections is 40 much wider than it was before the lifting.

The middle section A^2 has a different mounting and a different lifting movement. It will be raised, together with section A^3 , by lifting up the marginal frame 45 at the joint S^2 . That will draw A^3 to the left slightly till projections T^2 on that section ride over stops T on the side rails D. Section A^2 will be guided into the elevated position of Fig. 1 by short link g^3 connecting it with stud g^2 (see Fig. 5) and at the 50 right by the longer link G connecting it with stud h. In this position it will be locked by a bar g^1 having a notch on its under side which engages a pin g^5 on lug g^4 . Section A^3 will be guided at its left 55 end by a link H connecting it to stud h and locked by the aforesaid stops T in its raised position of Fig. 1. It will be observed that the lifting has drawn sections 60 A^2 and A^3 much closer together than they are in the horizontal position of Fig. 2 and has also increased somewhat the gap between A^1 and A^2 .

To lower the sections it is, of course, 65 merely necessary to release the aforesaid

locks which uphold them, whereupon they will fall back into the horizontal positions shown in Fig. 2.

What we claim as new and desire to 70 secure by Letters Patent is:

1. A hospital bed comprising a supporting frame, and a bed spring thereon including a series of bottom frame-sections individually mounted on the said supporting frame, all of said sections being 75 movable relative to each other and also longitudinally with respect to said supporting frame, a set of upright helical springs on each section, a marginal top frame for said springs hinged in sections corresponding to 80 said bottom frame-sections and means for adjusting the angular relation of the aforesaid sections to the supporting frame.

2. A hospital bed comprising a supporting frame, and a bed spring thereon including a series of bottom frame-sections all of which are separately linked to said supporting frame so as to be movable longitudinally with respect thereto and also with respect to each other, a set of helical springs 90 on each of said frame-sections, a marginal top frame for said springs hinged in sections corresponding to said bottom frame-sections, and means for adjusting the angular relation of the aforesaid sections to the 95 supporting frame.

3. A hospital bed comprising a supporting frame and a bed spring thereon, including a series of bottom frames movably mounted in said supporting frame and capable of assuming differing angular relations with respect to said supporting frame and to each other, and all movable longitudinally with respect to said supporting frame, 100 means for supporting the bottom frames in adjusted angular relation with respect to the supporting frame, a set of helical springs on each of said bottom frames, and a marginal top frame for said springs connected thereto and hinged in sections corresponding to said bottom frames.

4. A hospital bed comprising a supporting frame and a bed spring thereon, including a bottom frame formed of disconnected sections all of which are capable of longitudinal movement relative to said supporting frame, individual mounting links for the respective bottom frame sections, a series of upright helical springs mounted in groups on and movable with the several bottom frame sections, and a top frame formed of sections pivoted on lines disposed opposite the spaces between the respective bottom frame sections.

5. A hospital bed comprising a supporting frame and a bed spring thereon, including a bottom frame formed in sections supported by said frame and movable so as to be capable of assuming differing angular relations with respect to said supporting 125

frame and all movable longitudinally with respect to said supporting frame, long mounting links at one end of the respective sections, means supporting the other ends 5 of the sections closer to the supporting frame when the frame sections are moved to their angular positions, a series of upright helical springs seated in groups on the several frame sections, and a foldable retaining 10 frame for said springs.

6. A hospital bed comprising a supporting frame and a bed-spring thereon including a bottom frame formed in three sections movably connected to the supporting frame, 15 said sections being longitudinally separable and having the middle section spaced farther from the foot section than from the head section when the spring is horizontal, together with a series of upright helical 20 springs seated in groups on the respective sections, and marginal frames for said springs foldable at points opposite the gaps between said sections.

7. A hospital bed comprising a bedstead 25 and a bed-spring thereon including a bottom frame formed in three sections, said sections being longitudinally movable with respect to the said bedstead, upright helical springs seated on said sections, foldable marginal 30 frames for said springs located approximately in the plane of the tops of said springs and means for setting the sections at different angles to the bedstead and maintaining them in that position.

35 8. A hospital bed comprising a bed frame,

a bed-spring thereon including a bottom frame formed in sections each section being mounted to pivot at one end on the bed frame, means for maintaining one of said sections in various adjusted positions, upright helical springs on the respective sections and a retaining frame for said springs foldable at points opposite the gap between 40 adjacent sections of said bottom frame.

9. A bed-spring of the coil type foldable 45 upwardly and downwardly at successive points on its top level and provided with head, middle and foot bottom frame-sections said middle and foot sections being arranged to separate at a downward fold, together 50 with a top frame jointed at each of the folding points and a group of helical springs between each pair of top and bottom frame sections.

10. A hospital bed comprising a bedstead, 55 a bed-spring of the coil type, foldable in three sections including an upwardly inclined section at the head and two oppositely inclined sections below the head section together with stops on the opposite ends of 60 the bedstead and for the two end sections, the three sections being hinged on the top level and separable from one another on the bottom level.

Signed at Long Island City, New York, 65
County of Queens, State of New York, this
19th day of September, 1922.

GEORGE F. SISBOWER.
LOUIS E. PITTONI.
